UNITED STATES PATENT OFFICE.

HENRY E. WAITE, OF NEWTON, MASSACHUSETTS.

DESIGN FOR A GUIDE FOR MAIL-PACKING MACHINES.

SPECIFICATION forming part of Design No. 26,439, dated December 22, 1896.

Application filed September 28, 1896. Serial No. 607,267. Term of patent 14 years.

To all whom it may concern:

Be it known that I, HENRY E. WAITE, of Newton, in the county of Middlesex and State of Massachusetts, have invented a new and original Design for a Guide for Mail Marking and Packing Machines, of which the following is a specification.

This invention relates to a new and original design for a mail marking and packing machine; and it consists in the novel features of shape and configuration hereinafter fully described and particularly claimed, and clearly illustrated in the drawings.

Reference is to be had to the accompanying drawings, and to the letters marked thereon, forming a part of this specification, the same letters designating the same parts or features, as the case may be, wherever they occur.

Figure 1 is a plan view of a guide for a mail marking and packing machine, showing my design. Fig. 2 is a front elevation of the same.

The leading feature of my design consists of the parallel flat surfaces connected by an oblique surface, and a surface at substantially a right angle to the straight surfaces. 25

The guide is rectangular in delineation, and has a surface *a* joined to a parallel surface *c* by an oblique curved surface *b*, from which latter a straight surface *d* extends at a right angle. The surfaces *a*, *b*, and *c* have an oblong aperture with straight edges. 30

I claim—

The design for a guide for mail-packing machines substantially as shown and described. 35

In testimony whereof I have signed my name to this specification, in the presence of two subscribing witnesses, this 24th day of September, A. D. 1896.

HENRY E. WAITE.

Witnesses:

A. D. HARRISON,
P. W. PEZZETTI.
